UNITED STATES PATENT OFFICE.

ALBERT A. SPERRY, OF MERIDEN, CONNECTICUT, ASSIGNOR TO C. ROGERS & BROS., OF SAME PLACE.

DESIGN FOR A SPOON OR FORK HANDLE.

SPECIFICATION forming part of Design No. 14,320, dated September 18, 1883.

Application filed August 6, 1883. Term of patent 14 years.

To all whom it may concern:

Be it known that I, ALBERT A. SPERRY, of Meriden, in the county of New Haven and State of Connecticut, have invented a new Design 5 for a Spoon or Fork Handle; and I do hereby declare the following, when taken in connection with the accompanying drawing and the letters of reference marked thereon, to be a full, clear, and exact description of the same, 10 and which said drawing constitutes part of this specification, and represents a face view.

This invention relates to a design for the handle of spoons, forks, and like articles of table-service; and it consists in the configuration and ornamentation of the handle, as shown 15 in the accompanying illustration and herein-after described.

The handle from the central boss gradually expands toward the end, where it terminates 20 in oval shape. On the face and at the tip is a band, *a*, of "egg and dart" ornamentation, corresponding to the shape of the end of the handle. At the base of this band, and transversely across the face of the handle, is a band, 25 *b*, consisting of a series of rose ornaments, with

a light border upon each edge of the band. Between the band *b* and the band *a* is a flori- 30 ated branch. Below this band *b* the surface is left plain to form a panel. Below this panel is a narrow band, *c*, transversely across the face, and on the panel below this band *c* is the 35 representation of floriated tracery, as shown in the accompanying illustration.

I claim—

The design for spoon and fork handle, 35 consisting of the ornamented band *a* at the tip of the handle, corresponding to the shape of the tip, the ornamented band *b* at the base of the band *a*, the face between the said band having a floriated ornament, a plain panel below the 40 band *b*, and a transverse ornamented band at the lower end of the panel, with the panel below the said band ornamented with floriated tracery, as shown in the accompanying illustration.

ALBERT A. SPERRY.
